UNITED STATES PATENT OFFICE.

ARTHUR E. LINDNER, OF BROOKLYN, NEW YORK, ASSIGNOR TO THE L. AND H. SPECIAL MACHINE CO. INC., OF NEW YORK, N. Y., A CORPORATION OF NEW YORK.

MACHINE FOR SEWING SNAP FASTENERS.

Application filed November 20, 1919. Serial No. 339,393.

To all whom it may concern:

Be it known that I, ARTHUR E. LINDNER, a citizen of Germany, and a resident of the borough of Brooklyn, county of Kings, city 5 and State of New York, have invented certain new and useful Improvements in Machines for Sewing Snap Fasteners, of which the following is a specification.

The present invention relates to improvements in machines and methods for sewing snap fasteners, and has for an object to provide a machine of this character, by means of which snap fasteners may be sewed in a more secure and accurate manner than 10 heretofore, and more particularly I propose to provide a machine which will produce stitches extending between the eyelets of the fastener, and also between the eyelets and the periphery, to the end that the same 15 will be more securely fastened, and will lay flatter on the material and will furthermore be less subject to twisting strains than is the case when such fasteners are only secured by stitches extending between the eyelets.

20 A further object is to provide a machine of simple and reliable construction, and which may be operated with facility, and a still further object is to provide a machine capable of adjustment to accommodate snap 25 fasteners of different dimensions.

With these and other objects in view, an embodiment of my invention is shown in the accompanying drawings, and this embodiment will be hereinafter more fully described with reference thereto, and the invention will be finally pointed out in the 30 claims.

In the accompanying drawings, Fig. 1 is 35 a plan view of the present embodiment of my invention with a portion of the machine head broken away.

Fig. 2 is a side elevation.

Fig. 3 is an end view.

Fig. 4 is an enlarged vertical sectional 40 view along the line 4—4 of Fig. 1.

Fig. 5 is an enlarged detail plan view of 45 the end of the fastener supporting arm.

Fig. 6 is an end view thereof.

Fig. 7 is a diagrammatic plan view of 50 a snap fastener and showing the successive positions at which the needle is operated relatively thereto.

Fig. 8 is a plan view of a snap fastener 55 sewed to the material according to the present embodiment of my invention.

Figs. 9, 10, and 11 are diagrammatic views of the three cooperating cams employed in the machine for producing the movement of the snap fastener supporting arm.

Similar reference characters indicate corresponding parts throughout the several figures of the drawings.

Referring to the drawings, the embodiment of my invention disclosed therein comprises a base plate 10, provided with a head 60 11 of the usual type in sewing machines, having a horizontal drive shaft 12 extending rearwardly, and provided with a pulley 12^a adapted to be engaged by a suitable belt, and provided in its forward end with a reciprocating needle bar 13, carrying a needle 14, adapted to reciprocate through a needle hole 15 in the throat plate 16, and cooperate with a looper (not shown) beneath the base to 65 form a stitch. The above referred to parts 70 are old in sewing machines, and may be of any usual and desirable type.

Adjacent the upright portion of the head rising from the base plate, and extending 75 forwardly therefrom, there is provided in 80 the base plate a slot 17 in which is mounted a slide piece 18, fixed by screws 18^a upon the end portion 19 of a slide bar 20, extending from the said portion 19, which is 85 disposed at right angles to the slide piece 18, diagonally across the bed plate in a 90 rearward direction, where it is provided with another end portion 21 at right angles to the portion 19, and slidably supported in a guide bracket 22 having a laterally extending flange 23 extending beneath and secured to the under side of the base plate by bolts 24, which also in addition to other bolts 25 95 secure to the rear end of the base plate 10 a rearwardly projecting supporting plate 26, the portion 21 of the bar 20 being guided between the side of this plate 26 and a flange 27 on the bracket 22. The slide piece 18 and the bar 20 are adapted to have equal sliding movement longitudinally of the bed plate.

Upon the upper surface of the portion 19 of the bar 20, there is rigidly secured a strip 28 by means of screws 29, and upon which 100 is swivelly secured by means of a button stud 30, a U shaped supporting member 31, the button stud 30 passing through the base thereof, while between the upstanding side portions there is pivotally mounted upon a transverse pin 32 a forwardly extending 105 110

block member 33 guided at its forward portion by angle pieces 34 and 35 secured to the front face of the member 31 by screws 36, these screws also securing in place a laterally extending ear 37, having upwardly extending lugs 38 and 39 interposed between the angle pieces and the faces of the member 31, the under surface of the ear being sufficiently above the base 10 to secure 10 the strip 28 upon turning movement of the member 31.

To the upper surface of the block member 33 there is secured the end of a forwardly extending elongated arm 40, retaining 15 screws 41 and 42 engaging a slot 43 in said arm to permit of its longitudinal adjustment. At its forward portion the arm 40 is bent at an inclination downwardly as at 44 to a flat engaging end portion 45. An 20 elongated U shaped spring 46 having its transverse portion engaging across the upper surface of the arm 40 and its ends secured in the upright portions of the supporting member 31 by screws 47, bears down 25 upon the arm 40 and yieldingly engages the end portion 45 with the throat plate, or more properly the material disposed upon the throat plate, and to which the snap fastener is to be secured.

30 The arm 40 may be raised to lift the end 45 from the throat plate by pressure upon a pedal lever 48, preferably hinged to the floor, through the intermediary of a lever 49 pivotally mounted at 50 upon the side of 35 the head 11, the end of the upper arm of which is provided with an L shaped rod 51, connected by a chain 52 to a loop 53 secured to the said arm 40, while the other arm extending through a slot 54 in the base 40 is connected by a chain 55 extending over a roller 56 to a pedal.

45 The swivel mounting of the member 31 supporting the arm 40 upon the longitudinally slid able parts 20 and 18, permits of the end of the arm having universal movement upon the throat plate to assume any desired position, and the mechanism for producing such movement will be presently more fully described.

50 The end 45 of the arm 40 is provided with a rectangular cut-out portion 57, the front side being open, the side walls having grooves 58 therein to receive a circular snap fastener A, provided in the present instance with four equally spaced radially disposed eyelets B, C, D, and E, the sewing thread F adapted to extend between the eyelets and also from the eyelets over the periphery, as shown in Fig. 8, being looped at the under side of the material by a holding thread as is usual in machine sewing. Recesses 59 and 60 are provided in the corners of the cut-out 57 in radial alignment with the eyelets B and E to provide a free-way for the 60 needle, the peripheral portions of the fas-

tener in radial alignment with the eyelets C and D being unenclosed.

The fastener, after being inserted in the end of the arm, is yieldingly held in place by means of a plunger pin 61, disposed in 70 a passage 62 in the forward end of the arm at one side of the cut-out 57, and projecting into the groove 58 into engagement with the periphery of the fastener forwardly of its transverse center line, the outer end 75 of the pin being supported upon the end of a flat spring 63 pinned to the arm 40 as at 64, and adapted to have lateral movement. A flat spring 65 adapted to have vertical movement is also pinned to the arm 80 40 at 66, and carries an angular bevelled cam piece 67, the point of which is adapted to pass at the inner side of the spring 63 upon depression of the spring 65, the bevelled surface of the cam piece causing the lateral outward movement of the spring 63, and disengagement of the pin 61 from the fastener. This action is brought about during raising of the arm by depression of the 85 pedal lever 48 by engagement of the spring 65 with a stop piece 68 mounted upon the head 10, and having a laterally bent portion 69 in the path of the said spring.

According to the present embodiment of 95 my invention, the end of the arm carrying the fastener assumes eight different positions relatively to the line of movement of the needle, that is interiorly of each of the four eyelets, and exteriorly of them radially 100 outwardly of the periphery, and has sixteen different movements during a complete 100 cycle of operation, that is during the sewing of one fastener.

These movements are illustrated in Fig. 105 7, the first stitch being within the eyelet B, the second within the eyelet E and the third stitch within the eyelet B again. These three preliminary stitches securely hold the fastener to the material for the subsequent 110 operations. The fourth stitch is exteriorly 110 of the eyelet B, the fifth stitch interiorly of the eyelet B, the sixth stitch interiorly of the eyelet C, and the seventh stitch exteriorly thereof, and the eighth stitch interiorly; the ninth stitch interiorly of the eyelet D, the tenth stitch exteriorly thereof, the eleventh stitch interiorly; the twelfth stitch interiorly of the eyelet E, the thirteenth stitch exteriorly thereof, and the fourteenth, fifteenth, and sixteenth stitches 115 interiorly thereof. These last three stitches 120 within the eyelet E form a knot like structure at the under side of the material, which secures the thread against unraveling. The 125 thread is then cut, preferably by automatic means, such as shown for instance in my U. S. Patent No. 1,193,906, dated August 8, 1916, for "Apparatus for cutting thread in sewing machines." After the sixteenth 130 stitch the arm 40 moves so that it is in a

position relative to the needle for making the first stitch of the next sewing operation.

An arm 70 is secured to the upper side of the ear 37 of the swivelly mounted member 31 of the arm 40 by means of screws 70^a, and is provided at its end with a roller 71, engaging the cam face of a swinging cam lever 72, pivotally mounted at 73 on the end portion 21 of the slide bar 20, the roller being held in engagement with the said cam face by means of a coil spring 74, connecting the under side of the arm 70 at 75 to the under side of the cam lever 72 at 76.

The cam face of the cam lever comprises four parts, 77, 78, 79, and 80, in stepped relation in the order designated by the numbers 1, 2, 3 and 4 as shown and connected by inclined surfaces as at 81 and each provided with slotted tongues 82 engaging recesses 83 in the flared end of the cam lever, and adjustable to regulate the relative rises of the cam parts by means of set screws 84.

At its rear end the cam lever is provided with a slot 85 engaged by a roller 86 provided on the end of a transversely slidable bar 87 mounted at the under side of the support 26 in a slide channel 88, being held in place at its under side by a cross piece 89, secured by screws 90. A depending arm 91 is provided at the inner end of the bar 87 upon which is mounted a roller 92 engaging the peripheral cam surface of a cam 93, mounted upon a cam shaft 94, journaled in depending bearing brackets 95 and 96 at the under side of the support 26, a slot 97, being provided in the said support between the brackets 95 and 96, through which the cam rotates.

The cam shaft is driven from the drive shaft 12 by a train of reducing gears 98, 99, 100 and 101, at a ratio of 1 to 16, the small and large gears 98 and 101 being respectively mounted on the drive shaft and the cam shaft, while the large and small gears 99 and 100 are mounted on a stud shaft 102 journaled in a bearing bracket 103, provided on the support 26 and braced at its outer end by a bar 104 connected to the respective ends of the shafts 12 and 102. The roller 92 is yieldably held in engagement with the cam 93 by means of a coil spring 105 extending between the stud 106 at the under side of the bar 87 and the cross piece 89.

The swinging of the cam lever 72 through the action of the cam 93 causes engagement of the respective cam portions 77, 78, 79, and 80, with the roller 71, thereby swinging the arm 70, and producing the transverse movement of the arm 40, the slot connection 85 between the cam lever 72 and the bar 87 permitting longitudinal movement simultaneously through the mounting

of the cam lever 72 on the slide bar 20 without disturbing this relation.

A transversely disposed lever 107 is pivoted at 108 to the base plate 10, and extends beneath the ear 37 of the supporting member 31, being provided with a slot 109 engaging an upstanding pin or stud 110 on the slide piece 18, and is adapted by its swinging movement to cause longitudinal movement of the said slide piece, the bar 20, the supporting member 31, and the parts 75 carried thereby, i. e. the cam lever 72, the arm 70, and the snap fastener supporting arm 40.

At the outer end of the lever 107, there is swivelly mounted at 111 a turn block 112, 80 having an upstanding ear 113 thereon, to which is pivotally connected one end of a rod 114, its other end being pivotally connected to an upstanding arm 115 of an arcuate plate 116, secured to a cylindrical sleeve 117, mounted on the transversely disposed shaft 118 journalled at its ends in bearing brackets 119 and 120 on the support 26. A rearwardly projecting arm 121 is also provided on the plate 116 bent transversely as at 122 and provided at its end with depending ears 123 rotatably supporting a roller 124 which rides upon the peripheral surface of a cam 125 mounted on the cam shaft 94 and adapted to swing the lever 107 through the intermediary of the arms 121 and 115 and the rod 114.

The cam 125 comprises sixteen separate cam portions mounted in the annular channel 126 of an annular supporting member 127, and individually adjustable by means of slots 128 therein engaged by set screws 129 to regulate the relative positions of the individual cam surfaces, to accurately adjust the swinging movement of the lever 107, and thereby the longitudinal movement of the arm 40.

A coil spring 130 extending between a stud pin 131 on the turn block 112 and a pin 132 on the support 26 normally draws the lever 107 rearwardly and holds the roller 124 in engagement with the cam 125. A cut-out portion 133 in the arm 70 accommodates the movement of the turn block 112.

The transverse movement of the arm 40, it will be understood, is produced through the cooperative action of the cam surfaces 77, 78, 79, and 80; and the cam 93, while the longitudinal movement of the said arm is produced through the action of the cam 125, and by adjustment of the individual cam parts 77, 78, 79, and 80, and the individual cam parts of the cam 125, both the transverse and longitudinal movement may be accurately adjusted to produce any desired throw and thereby enable the sewing of snap fasteners of different sizes upon the same machine. In Figs. 9, 10, and 11, I

have illustrated diagrammatically the three cams and have numbered the sixteen parts of the cams 93 and 125 and the four parts of the cam lever 72 with the numbers 1 to 16 to indicate the positions at which there is independent transverse movement, independent longitudinal movement, and simultaneous transverse and longitudinal movement. Thus, at the positions 1, 2, and 3, there is independent transverse movement from the eyelet B to the eyelet E and back to the eyelet B, while in the position 4 there is simultaneous transverse and longitudinal movement from the eyelet B to the exterior peripheral portion of the fastener in radial alignment with the eyelet B. From the position 4 to the position 5 there is simultaneous transverse and longitudinal movement back to the eyelet B, while from the position 5 to the position 6 there is independent longitudinal movement, etc.

I have illustrated and described a preferred and satisfactory embodiment of my invention, but it is obvious that changes may be made therein within the spirit and scope thereof, as defined in the appended claims.

I claim:

1. In a sewing machine of the character described, a stitch forming mechanism including a needle, a supporting member adapted to support an article to be sewed having eyelets, said member adapted to have longitudinal and transverse movement relatively to said needle, cam means for causing said transverse movement, said cam means having individual cam parts separately adjustable to adjust the extent of said transverse movement, and cam means for causing said longitudinal movement.
2. In a sewing machine of the character described, a stitch forming mechanism including a needle, a supporting member adapted to support an article to be sewed having eyelets, said member adapted to have longitudinal and transverse movement relatively to said needle, cam means for causing said transverse movement, and cam means for causing said longitudinal movement, said last mentioned cam means having individual cam parts separately adjustable to adjust the extent of said longitudinal movement.
3. In a sewing machine of the character described, a stitch forming mechanism including a needle, a supporting member adapted to support an article to be sewed having eyelets, said member adapted to have longitudinal and transverse movement relatively to said needle, primary cam means for causing said transverse movement having cam parts corresponding in number to the number of transverse positions and secondary cam means adapted to cause the movement of said primary cam means and having cam parts corresponding to the number of transverse movements during the sewing of one article, and cam means for causing said longitudinal movement.

4. In a sewing machine of the character described, a stitch forming mechanism including a needle, a supporting member adapted to support an article to be sewed having eyelets, said member adapted to have longitudinal and transverse movement relatively to said needle, primary cam means for causing said transverse movement having individual cam parts separately adjustable to adjust the extent of said transverse movement and corresponding in number to the number of transverse positions and secondary cam means adapted to cause the movement of said primary cam means, and having cam parts corresponding to the number of transverse movements during the sewing of one article, and cam means for causing said longitudinal movement, said last mentioned cam means having individual cam parts separately adjustable to adjust the extent of said longitudinal movement.

5. In a sewing machine of the character described, a stitch forming mechanism including a needle, a supporting member provided with an opening adapted to receive and support an article to be sewed having eyelets, a pin in the plane of and adapted to project into said opening to engage said article to retain the same therein against removal and turning movement, and spring means adapted to yieldably project said pin into said opening, and permit its withdrawal.

6. In a sewing machine of the character described, a throat plate, a stitch forming mechanism including a needle, a supporting member provided with an opening adapted to receive and support an article to be sewed having eyelets, a pivotal support at one end of said supporting member, spring means adapted to yieldably engage its other end with said throat plate, means for raising said end from said throat plate, a laterally movable pin adapted to project into said opening to engage said article to retain the same therein against removal and turning movement, spring means adapted to yieldably project said pin into said opening, and means adapted to withdraw said pin from said opening upon the raising of said supporting member, to permit the removal of said article and the insertion of another one, said pin adapted to be projected into said opening upon the lowering of said supporting member.

In testimony that I claim the foregoing as my invention, I have signed my name hereunder.

ARTHUR E. LINDNER.
